FISH LURE

Eugene W. Cooper, San Francisco, Calif.

Application March 26, 1951, Serial No. 14,631

Term of patent 7 years

(Cl. D31—4)

To all whom it may concern:

Be it known that I, Eugene W. Cooper, a citizen of the United States, residing at San Francisco, State of California, have invented a new, original, and ornamental Design for a Fish Lure, of which the following is a specification, reference being had to the accompanying drawing, forming a part hereof.

Fig. 1 is a top plan view of a fish lure, showing my new design;

Fig. 2 is a view in side elevation of the same; Fig. 3 is a bottom plan view of the same; and Fig. 4 is a view in front elevation of the same.

The essential features of my invention reside in the portions shown in full lines.

I claim:

The ornamental design for a fish lure, substantially as shown and described.

EUGENE W. COOPER.
